TRANSFORMER CLUSTER RACK

Samuel J. Ward and Milton C. Cross, Houston, Tex., assignors to Universal Pole Bracket Corporation, Houston, Tex., a corporation of Texas

Application March 30, 1953, Serial No. 345,538

9 Claims. (Cl. 248—230)

This invention pertains to transformer cluster racks and is a continuation-in-part of our co-pending application S. N. 250,234, filed October 8, 1951, now abandoned.

It is an object of the invention to provide a cluster rack which can be fastened to a pole to support the transformer or transformers at any desired level and in any desired azimuthal position.

It is another object of the invention to provide a rack by which the transformers can be supported closely adjacent the pole.

It is another object of the invention to provide a cluster rack for poles which may be quickly connected and disconnected.

Another object of the invention is to provide a rack upon which a plurality of transformers may be supported.

Another object of the invention is to provide a cluster rack which can be securely positioned regarding a telephone pole so that the transformers may be securely supported thereon.

Another object of the invention is to provide a plurality of relatively closely spaced cluster racks so that the support framework of the transformer may be connected to adjacent cluster racks properly spaced so as to support the transformer closely adjacent the pole.

Another object of the invention is to provide a cluster rack for transformers which may be firmly clamped about the pole without materially weakening the pole by boring, cutting, high localized stresses, and the like.

A further object of the invention is to provide a cluster rack to which as many as three transformers may be supported while still leaving adequate climbing space for workmen on the pole.

Another object of the invention is to provide a cluster rack which without change of size is capable of supporting either small or large transformers, so as to provide a maximum of utility with a minimum of manufacturing cost.

Another object of the invention is to provide a cluster rack for poles with an outstanding double arm to support a plate to which the transformer is in turn connected, whereby the transformer will be adequately supported against side thrusts such as that due to unequal tension in the wires connected to the transformer or due to wind blowing against the transformer.

A still further object is to provide a brace for attachment to a transformer cluster rack so that relatively large transformers may be affixed to the cluster rack and properly braced relative to the telephone pole.

Another object is to provide a rack which without change of size of its parts is adapted to be secured to poles of different diameters, and to this end a further object of the invention is to provide a rack having retaining bolts long enough to fasten the rack to a large diameter pole and having extending arms which have openings therein to allow for attachment of the rack to a relatively small diameter pole so that the retainer bolts

2

may project through the arms which support the transformer.

Other and further objects of the invention will be readily apparent when the following description is considered in connection with the accompanying drawings wherein:

Fig. 1 is a side elevation showing a pole to which the cluster racks have been attached and whereon three transformers are supported on a pair of cluster racks suitably adjusted.

Fig. 2 is a side elevation to a larger scale showing two transformers, one large and one small, which are attached to a pair of spaced cluster racks which have been clamped about the pole.

Fig. 3 is a side elevation to a still larger scale of a portion of the device shown in Figure 2 and in which a brace has been affixed between the supporting lug and the transformer supporting plate to give additional strength to the bracket. Fig. 3 also shows a horizontal plate bolted to the vertical supporting plate to provide spaced connections for very large transformers having two horizontally spaced connectors at each level. Also shown in Fig. 3 in phantom is a vertical plate used when a very small transformer is supported from a single bracket.

Figs. 4, 5, 6 are similar transverse sections, Figure 5 being taken on the line 5—5 of Fig. 2, and looking down on cluster racks affixed to small, medium, and large poles respectively.

In Fig. 1, a pole 2 is shown as having been positioned in the ground and the usual crossbar 3 serves to support wires. The pole is also shown as serving as a support for a plurality of transformers such as 4, 5, and 6 which may be used in connection with three phase power transmitted by the wires.

This cluster of transformers is shown in Fig. 2 more in detail. The transformers are supported on the pole by the racks 8 and 9 which are identical. Two such racks are provided about the pole each providing brackets 10, 11, and 12 upon which the transformers 4, 5 and 6 respectively are supported. In this manner a single pole may serve to support a number of transformers and they may be securely fastened by using the racks 8 and 9 in combination.

Fig. 5 is a transverse view through the pole and illustrating the manner of assembling the racks on the pole for supporting the transformers. The pole 2 is illustrated as receiving the rack 9 which is shown as being made up of a plurality of arcuate bodies in the form of straps or curved plates 13, 14, 15, 16. Each of these plates comprises a bar or strap of metal which is arcuately curved to fit generally around the periphery of the pole 2. The initial curve is such as to fit a medium diameter pole as shown in Figure 5. Although the fit will not be perfect on smaller poles as shown in Figure 4, or larger poles as shown in Figure 6, the plates will tend to bend to fit closely around smaller and larger poles when tightened up as hereinafter described.

The ends of each plate are bent outwardly from the arcuate portion to form the ears 17 on the end thereof. Each plate is provided with an opening in each ear to receive the bolts 20 therethrough. As is apparent from the drawings, the ears are not radially directed but are disposed so that the adjacent ears of adjoining straps are parallel and perpendicular to the bolt 20 therethrough. Otherwise stated, the angle between the ears on each strap is equal to 360 degrees divided by the number of straps, which is ninety degrees.

It will be seen that the bolts are of sufficient length to go through two of the ears 17 which may be spaced apart depending upon the diameter of the pole 2. Each bolt 20 is arranged to receive the supporting or back-up

nuts 21 behind the ears 17 and to receive the nuts 22 on the ends of the bolt to draw the ears 17 of the adjacent plates together. The nuts may be adjusted as desired so as to cause a tight fitting of the plates about the pole.

Plate 13 is a simple strap of steel with bent ends, while to one or more of each of the other plates 14, 15, 16 there are welded the lateral projecting arms 25 and 26 which go to make up a bracket by having a supporting plate 27 welded to the arms and supporting them in spaced relation. Each support plate 27 is provided with 10 vertically spaced upper and lower holes 28, 29 to receive the transformer bolts as hereinafter described. The double arms together with the curved plates and supporting plates form a rigid boxlike structure of great strength which can take side thrusts due to wind or tension of the 15 wire.

If only one of the racks such as the rack 9 is to be used, then it can be assembled and the transformer or transformers supported on the vertical plates 30 which are bolted to plate 27 as shown in dotted lines in Figure 3. Plate 30 has holes such as 31 therein vertically spaced the proper distance to receive the transformer bolts. This arrangement is suitable for very small transformers. For larger transformers it is necessary to utilize two of the racks in spaced relationship upon the pole 2 as seen in Fig. 2 and the racks 8 and 9 will be thus employed. When the transformers are connected, one of them may be a small transformer, such as 32 while the other may be a large transformer such as 33 or any suitable combination of transformers.

The plates 14, 15, 16, are each provided with a lug such as 40 extending longitudinally along the pole and arranged to receive the lag screws such as 42 which may be driven into the pole. In this manner the rack will be securely anchored and any torque tending to twist the rack from position will be resisted by the lag screw 42.

In Fig. 2 there is shown the manner of securing the transformers to the racks. Referring to transformer 32 the upper bolt 43 of the transformer will pass through the lower hole 29 of the plate 27 of the upper rack whereas the bolt 44 which is the lower bolt on the transformer will pass through the hole 28 in the upper end of the plate 27 of the lower rack. In the case of the large transformer 33 the bolts 43 and 44 will pass through the upper and lower openings in the plates 27 respectively. In this manner two of the racks with identical brackets 10, 11, 12 on all three sides are adapted without alteration to take care of different size transformers when utilized at the same time on the same pole.

Large transformers, such as the transformer 33, may weigh as much as five thousand pounds. Hence, such transformers normally tend to exert a greater force on the upper and lower cluster racks in a direction to cause them to slide downwardly of the pole. This tendency is counteracted when the transformer is secured to the cluster racks in the manner shown at the right hand side of Fig. 2, where the means for securing the lower end of the transformer to the support or bridging plate 27 is located at a horizontal level below the level of the clamping bolts 20, and the means for securing the upper end of the transformer to the upper support or bridging plate 27 is located at a horizontal level above the level of the bolts 20 which clamp the arcuate bodies of the upper bracket set to the pole. With the transformer so secured to the upper and lower bracket sets, the arcuate bodies of both bracket sets are caused to exert their maximum clamping pressure against the pole along their lower edges and thus tend to bite into the pole at those places. This gives maximum resistance to the tendency of the arcuate bodies 13 to slide downwardly of the pole.

Particular attention is directed to the opening 48 in each of the bracket arms. This opening is to receive the ends of the bolt such as 20 when an exceptionally small pole is utilized and the straps may be of a length and close enough together to allow the bolt 20 to project

into the opening 48. This will avoid cutting off the bolt or bending of the parts as the case may be. This is illustrated in Figure 4. It is also to be noted that in this situation the back-up nuts 21 are omitted, the ears 17 being closely adjacent each other.

The openings perform an additional function in that they facilitate deformation of the curved plates 13, 14, 15 and 16 as they are clamped against poles of different diameter while weakening the arms 25 to a minimum extent. As shown in the drawings, the brackets are curved to fit a pole of the diameter shown in Fig. 5. When the brackets are clamped about a pole of different diameter, the openings facilitate the slight bending of the arms 25 which must take place. The openings preferably are elongated in the direction of the arms 25 and are spaced from both the inner and outer ends of the arms. Hence, the openings lie in a relatively neutral area as far as the portions of the arms which take a strain in the supporting of the transformers.

Attention is directed to the brackets at the right of Figure 2 supporting the heavy transformer 33. If the transformer is of very heavy weight there can be added the Z-brace 55 which is a short flat plate with the bent ends 51 and 59 thereon which may be attached at one end to the plate 27 by means of the bolt 4 and may be attached at the other end to the extension or lug 40. In this manner a rigid box-like structure is provided which includes the lug 40, plate 27, arms 25 and 26 and the brace member 55. The Z-braces may also be used in the case of very light transformers supported on a single-rack.

It will be understood that the Z braces may be omitted in the case of medium weight transformers, even though the transformer bolts are spaced far apart as shown at the right of Figure 2. On the other hand, in the case of extra heavy transformers which are provided with four bolts (two upper and two lower) instead of two bolts 43, 44 as previously described, there is provided, as shown in Fig. 3, a horizontal plate 57 secured to each plate 27 by bolt 58. Bolt 58 also holds the outer end of the Z brace in this case. Each plate 57 has two horizontally spaced holes therethrough to receive the transformer bolts.

Broadly, the invention contemplates one or more racks which may be suitably affixed to a suitable pole and adjustable as to size to fit various situations.

While the invention has been described and claimed in connection with the support of transformers, it is to be understood that other objects of substantial weight may be secured to the cluster rack for support from poles, and the claims are to be so construed.

What is claimed is:

1. A transformer cluster rack for supporting transformers on poles comprising a plurality of strap iron arcuate members to fit about the pole, the ends of each member being bent outwardly from the arcuate pole portion, bolts joining the ends to clamp the members about the pole, adjustable means to tighten the bolts and lock them to the pole, a support arm extending laterally from at least one of said members, a transformer supporting member connected to the outer ends of said support arm to which a transformer may be affixed, a lug extending from each member having a support arm to engage against the pole, each of said lugs extending from its strap member at right angles to the direction of elongation of the strap member and at right angles to the direction of extension of the support arm from its strap member, and a brace connected at one end to said transformer support arm and at its other end to the lug of the member from which the support arm extends to support said arm.

2. A transformer cluster rack comprising a plurality of arcuate straps adapted to fit around a pole, each strap having apertured outturned ears on the ends thereof, an outwardly extending arm on at least one of said straps, each arm comprising two spaced apertured plates located

between said ears, means on each arm to support a transformer, bolts passing through each adjacent pair of said ears, the apertures in the plate being sufficiently large to receive said bolts, the axes of said bolts being aligned with the apertures in adjacent plates, whereby when said straps are secured to a small diameter pole the ends of said bolts can extend through the apertures in said plates, and a nut on at least one end of each of said bolts to secure said straps together.

3. The combination of claim 2 in which there is additionally a pair of nuts on each of said bolts behind the ears on each strap to back up the ears when the straps are adjusted to fit poles of such diameter as to leave space between adjacent pairs of ears of adjacent straps.

4. A transformer cluster rack comprising a plurality of arcuate bodies adapted to fit around a pole, each body having apertured outturned ears on the ends thereof, an outwardly-extending arm on at least one of said bodies, a vertically extending plate on each arm, said vertically extending plate having upper and lower vertically spaced apertures therethrough, an apertured vertically extending lug on each body, each of said lugs extending from its body at right angles to the direction of elongation of the body and at right angles to the direction of extension of the arm from said body, and a brace of generally Z-shape connected at one end to the lower end of each plate and at its other end to the lug on the adjacent body.

5. A transformer cluster rack comprising a plurality of arcuate bodies adapted to fit around a pole, each body having apertured outturned ears on the ends thereof, an outwardly extending arm on at least one of said bodies, a vertically extending plate on each arm, said vertically extending plate having upper and lower vertically spaced apertures therethrough, an apertured vertically extending lug on each body, each of said lugs extending from its body at right angles to the direction of elongation of the body and at right angles to the direction of extension of the arm from said body, and a second vertically extending plate bolted to said first plate, the second plate being longer than said first plate and having two pairs of upper and lower vertically spaced apertures therein, the first of said pair of apertures being spaced the same as those in the first said plate and the second said pair of apertures being spaced farther apart.

6. A transformer cluster rack comprising a plurality of arcuate bodies adapted to fit around a pole, each body having apertured outturned ears on the ends thereof, an outwardly extending arm on at least one of said bodies, a vertically extending plate on each arm, said vertically extending plate having upper and lower vertically spaced apertures therethrough, an apertured vertically extending lug on each body, each of said lugs extending from its body at right angles to the direction of elongation of the body and at right angles to the direction of extension of the arm from said body, and a horizontally extending plate having three horizontally spaced apertures therein and bolted to the vertically extending plate through the central one of said three apertures.

7. Supporting means of the character described comprising a pole, spaced upper and lower sets of brackets, each bracket set including a plurality of arcuate bodies fitting against the pole peripheral surface, each arcuate body having outwardly bent ends, means connecting the adjacent outwardly bent ends of the respective arcuate bodies and securing the arcuate bodies against the pole, spaced, substantially aligned outwardly-extending arms carried by at least one of the arcuate bodies of each bracket set, said arms being positioned between said bent

ends, a member connected to the outer ends of said arms and bridging the space between them, the member bridging the space between the arms of the arcuate member of the upper bracket set having an opening therein located horizontally above the level of the means connecting the outwardly bent ends of the arcuate bodies of said set to secure said bodies to the pole, and the member bridging the outer ends of the arms of the lower bracket set having an opening therein located horizontally below the level of the means connected to the outwardly bent ends of the arcuate bodies of said lower set to secure said bodies to the pole, a transformer mounted on both said brackets, and members passing through said openings in said bridging members of the upper and lower bracket sets and supporting said transformer.

8. Supporting means as set forth in claim 7 in which each of said arms has an opening spaced inwardly from its inner and outer ends and elongated in the direction of the outward extension of said arms to facilitate deformation of the arcuate bodies when being secured to poles of different diameters.

9. Supporting means of the character described comprising a pole, spaced upper and lower sets of brackets, each bracket set including a plurality of arcuate bodies fitting against the pole peripheral surface, each arcuate body having outwardly-extending ends, means connecting the adjacent outwardly-extending ends of the respective bodies and securing the bodies to the pole, an outwardly-extending arm carried by at least one of the arcuate bodies of each bracket set, said arms being positioned between said outwardly-extending ends of the respective arcuate bodies and being substantially aligned in a vertical direction and an attaching plate at the outer ends of each of said arms, a transformer, mechanical connections between said attaching plates and the transformer securing the transformer to the respective attaching plates for support therefrom, the mechanical connection between the transformer and the attaching plate of the upper bracket set being located horizontally above the level of the means connecting the outwardly-extending arms of the arcuate bodies of said upper bracket set to clamp the arcuate bodies of that set to the pole, the mechanical connection between the transformer and the attaching plate of the lower bracket set being located horizontally below the level of the means connecting the outwardly-extending arms of the arcuate bodies of said lower bracket set to clamp the bodies of that set to the pole whereby the transformer exerts a force on arcuate bodies of the respective bracket sets from which it is supported tending to force the lower edge of said arcuate bodies against the pole.
